APPLE CELLING AND SLICING MACHINE

John W. Pease, deceased, late of Rochester, N. Y.,
by Winnifred N. Pease, executrix, Rochester,
N. Y.

Application January 19, 1948, Serial No. 3,124

2 Claims. (Cl. 146—40)

1

The present invention relates to machines for seed-celling and slicing apples and similar fruits.

In the preparation of apples for cooking, canning and drying it is customary practice to first pare and core the apples. Then the apples are fed into a combined seed-celling and slicing machine for removal of the seeds and seed cells and for quartering the apples or dividing them into lesser divisions. In conventional seed-celling and slicing machines, the apples are dropped over a rotating spindle and guided by their cored holes to the slicing blades. Each apple is seated against the slicing blades and is held against rotation by these blades in a partially severed condition while the seed cells are being removed. The culling is effected by a rotary culling knife which is secured to the rotating spindle and which operates approximately at the axial center of the core of the apple. After culling, each apple is pushed through the slicing blades, and thus the operation of the machine is completed.

The slicing blades only enter into an apple prior to the seed-celling operation but even this partial entrance slightly weakens the apple and may result in the apple being split prematurely under the slightly expanding pressure of the culling knife at its center. This is particularly the case if the apple happens to be unusually soft and mellow. If the apple is split prematurely it is broken up into a lot of unusable fragments.

One object of the present invention is to provide an improved slicing unit which will not only prevent an apple from rotating during culling but which will also hold the apple against the possibility of fragments or pieces of the apple sliding outwardly longitudinally of the slicing blades before the apple is completely severed, so that tendency toward disintegrating expansion of the apple is obviated, and the slicing operation may be accurately completed after decelling.

Another object of the invention is to provide an improved slicing fixture for a machine of the character described in which the holding means is in the form of auxiliary slicing blades integral with or rigidly secured to the main slicing blades.

Other objects of the invention will be apparent hereinafter from the specification and from the recital of the appended claims.

In the drawings:

Fig. 1 is a fragmentary side view of a seed-celling and slicing machine constructed according to one embodiment of this invention;

Fig. 2 is a central vertical section on a greatly enlarged scale of the slicing spider or fixture of this machine;

Fig. 3 is a view similar to Fig. 2 but showing a more complete assembly of the machine including the feed spindle and seed-celling knife and showing an apple in the process of being celled;

Fig. 4 is a detail sectional view taken on the

2

line 4—4 of Fig. 2 looking in the direction of the arrows;

Fig. 5 is another central vertical sectional view of the slicing spider but taken in the plane of a different pair of blades from the plane of Fig. 2;

Fig. 6 is a plan view of the spider and its mounting;

Fig. 7 is a fragmentary plan view like Fig. 6 but showing an apple in seed-celling position and in horizontal section;

Fig. 8 is a perspective view of one of the major knife blades and of its auxiliary blade; and

Fig. 9 is a perspective view of one of the auxiliary blades.

Referring now to the drawings by numerals of reference, 1 denotes the frame work of the machine which is supported by legs 2 (broken away). Supported on the frame in a horizontal position is a mounting member 4 which is secured to the frame work by bolts 4' (Figs. 1 and 6). This mounting member has a central opening and secured within this central opening by lugs 6 and bolts 6' is a slicing spider 5. This spider is provided with two sets of slicing blades, the individual blades of each set being denoted at 3 and 7, respectively. The blades 7 are more steeply inclined than the blades 3 and have their upper cutting surfaces above the cutting surfaces of the blades 3. All of the blades are arranged radially and are inclined downwardly; and their lower ends are fixed to a stationary sleeve 8.

11 denotes the central feed spindle of the machine. This spindle is provided with an enlarged portion 10 which is formed at its lower end with a shoulder 9 that rests upon the upper end of the sleeve 8. The spindle turns in the sleeve 8 and may be driven, for instance, by the bevel gearing 13 from any suitable source of power according to conventional practice.

10 The enlarged portion 10 of the spindle has a flat portion 12 to which is secured the rigid seed-celling knife 14 (Figs. 3 and 7) by screws 15. This knife projects laterally from the spindle 11 just above the blades 7 and is semi-circular in form. It is narrower at the top than at the bottom and is inclined slightly upwardly in a direction opposite to that of the rotation of the spindle as disclosed more particularly in copending application Serial No. 3,125 filed January 19, 1948.

50 Thus, when a cored apple slides down on the spindle, the knife 14 makes an imperceptible track or channel in the core opening thereof without further mutilation of the apple despite the continuous rotation of the spindle.

55 16 denotes a vertically swinging arm or beam having a fork or bifurcation 17 at its free end. This arm is adapted to be oscillated up and down by conventional means. This arm is provided to insure correct positioning of the apple, which is 60 to be celled and sliced, with reference to the

celing knife. The cored apple drops by gravity over the rotating celing knife 14 and upon the slicing knives 7, and the said arm 16 and fork 17 have an amplitude of movement that carries the apple down to the precise position shown in Figs. 1 and 3 with the apple centered with reference to the celing knife and positively forced into engagement with the slicing blades 7. The configurations and position of the two sets of blades 3 and 7, as shown, are relatively such that the apple lodges upon and is partly entered by the blades 7 when brought to rest but does not contact the lowermost blades 3. This locks the apple against the tendency to rotate under influence of the celing knife 14 yet does not weaken the apple materially as would be the case were all of the blades to enter the apple at once. The upper portion of the apple remains solid except for the core hole.

In Figs. 3 and 7, the seeds and cells of the fruit are rather conventionally shown at C while the circle or kerf cut by the rotary seed-celling blade 14 is indicated at K in the latter figure.

When the apple happens to be soft and mellow, even the slight entry of the blades 7 into it may, however, weaken its structure sufficiently for it to split prematurely under the slightly expanding pressure of the celing knife 14 as that knife rotates in engagement with it. To counteract this, there is provided by the present invention means for resisting any such movement and for maintaining the fruit integral until the seed-celling operation is completed and until the downward slicing movement is completed. This means comprises a plurality of thin vertical auxiliary fin blades 19 which are mounted on the radial blades 7 to extend transversely thereof and to project laterally therefrom. Interlocking assembly of blades 19 on blades 7 is accomplished by forming complementary slots 20 and 21 in the undersides of the radial blades 7 and upper ends of the auxiliary blades 19, as shown in Figs. 2 and 9, respectively. The smaller blades are introduced upwardly from below so that the assembled blades each grasp the other and may be soldered, swedged or otherwise secured together. The blades 19 are preferably provided with cutting edges back off on all four sides as shown. They are positioned to engage the apple approximately midway radially between the celing knife 14 and the periphery of the apple.

With these simple auxiliary blades, the apple is effectively supported from within and the potential apple segments are prevented from spreading prematurely. These auxiliary blades are simple and inexpensive yet they perform the function of the more elaborate and uncertainly acting supports or grasping elements which have heretofore been provided and which are arranged around or outside of the fruits or other articles in process.

The upper limit of movement of the arm 16 is such that after an apple A has been seated on blades 7 and 19 the fork 17 withdraws sufficiently from its straddle of the spindle 11 to permit a following apple B to pass and to drop upon the first apple A while the seed-celling operation is being completed upon the first apple, as shown in Fig. 1. Whereupon the fork resumes its downward stroke and through the medium of the second apple B presses the first apple A through all of the blades 3 and 7 of the slicing device separating the apple into a plurality of detached segments that are suitably caught and deflected

below with the aid of deflectors 18. The same stroke places the apple B in seed-celling position, and so the operation of the machine proceeds.

While the invention has been described in connection with a particular embodiment thereof, it will be understood that it is capable of further modification and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described the invention, what is claimed is:

1. In an apple slicing machine, the combination with a vertically disposed rotary spindle, means for rotating the spindle, and means for thrusting a cored apple down the spindle, of a slicing spider concentric with said spindle and comprising a plurality of thin blades which are disposed radially of the spindle, and auxiliary blades mounted on the radial blades to extend axially of the spindle and to project laterally from opposite sides of the radial blades less than the distances between adjacent radial blades to hold an apple against expanding disintegration of the partially-severed apple when the apple is thrust down the spindle and through the spider.

2. In a seed-celling and slicing machine, the combination with a vertically disposed rotary spindle, and means for rotating said spindle, of a seed-celling knife secured thereto, a slicing spider mounted below said knife concentric with said spindle, said slicing spider comprising a plurality of blades which are disposed radially of the spindle and upwardly inclined from the center of said spindle outwardly, certain of said blades being inclined upwardly at a greater angle than others, means for thrusting a cored apple down said spindle and against the blades which are of greater upward inclination so that said blades may hold the apple against rotation during the seed-celling operation, auxiliary blades mounted on the more inclined blades intermediate the ends of said more inclined blades to extend axially of the spindle and to project laterally from said more inclined blades less than the distance between adjacent radial blades to hold the apple against expanding disintegration during the seed-celling operation, and means for actuating the thrusting means, after completion of a seed-celling operation to force the apple down the spindle through all of the blades of the spider.

WINNIFRED N. PEASE,
Executrix of the Estate of John W. Pease,
Deceased.
